UNITED STATES PATENT OFFICE.

ALPHONSE ALARY, OF ST. CASIMIR, QUEBEC, CANADA.

DOOR-HINGE.

1,318,824.

Specification of Letters Patent.

Patented Oct. 14, 1919.

Application filed October 18, 1917. Serial No. 197,188.

To all whom it may concern:

Be it known that I, ALPHONSE ALARY, a subject of the King of Great Britain, residing at St. Casimir, Portneuf county, 5 Province of Quebec, Canada, have invented certain new and useful Improvements in Door-Hinges; and I do hereby declare that the following is a full, clear, and exact description of the invention, such as will enable others skilled in the art to which it 10 appertains to make and use the same.

The present invention relates to door hinges and more particularly to hinges for supporting doors, gates or the like, and an 15 object of the present invention is to provide a hinge wherein the door or gate may be retained in open or closed position.

With the above and other objects in view which will hereinafter appear as the description continues, the invention consists 20 of the novel features of construction, combination and formation of parts as will be hereinafter more fully described and particularly pointed out in the appended claim.

25 In the accompanying drawings has been shown a simple and preferred form of the invention, it being, however, understood that no limitation is necessarily made to the precise structural details herein exhibited, 30 but the right is hereby reserved to any changes, alterations or modifications to which recourse may be had that come within the scope of the claim without departing from the spirit of the invention or sacrificing 35 the efficiency of the same.

In the accompanying drawings:

Figure 1 is a side elevation of the hinge embodying the present invention when applied to use and showing the door in one 40 position;

Fig. 2 is a similar view but showing the door in another or open position; and,

Fig. 3 is a detail perspective view.

Referring now more particularly to the 45 accompanying drawings wherein like and corresponding parts are designated by similar reference characters throughout the several views.

As shown herein a door casing is provided 50 having the floor portion 1 and the ceiling portion 2. A plate 3 is secured to the ceiling portion of the door casing having a lug 4 depending therefrom and this lug 4 is pivotally mounted within a socket 5 arranged 55 within the upper end of the swinging door 6. The lower edge of the door 6

has secured thereto a plate 7 and carried by the door is a vertical pin 8. This plate 7 is adapted to rest within a recess formed within the lower face of the door 6 and has 60 formed with one end thereof a vertical lugged projection 7' which also extends up within the door 6. The pin 8 extends through an opening formed in the opposite end of this plate and then within the door 6, and in this manner the lug projection 7' as well as the upper end of the pin 8 will hold the plate 7 within the lower face of the door 6. Countersunk within the opposite faces of this door 6 are the plates 20 and 70 these plates are secured within the door 6 and connected together by means of the screws 21. A screw 22 may also extend through the plate 7 so as to prevent the same from dropping downwardly. From 75 Fig. 2 of the drawings it will be noted that the plates 20 extend on the opposite sides of the plate 7 so as to take up any lateral strain upon the same and also due to the height of these plates 20 the lower edge of the door 6 80 will be greatly reinforced. Secured upon the floor portion of the door casing 1 is a shoe comprising a plate 10 having a depending flange 11 adapted to rest within the portion of the floor casing and a vertically ex- 85 tending flange 12 which is arranged above the floor of the door casing. This shoe is provided with an opening 13 through which may extend the pin 8 and the pins 4 and 8 provide a pivoted support for the door 6. 90 Depending from the plate 7 are the lugs 14 and between these lugs is journaled a roller 15. This roller 15 is adapted to ride upon the upper edge of the flange 12 during the opening and closing movement of the door. 95 Formed within the upper edge of the flange 12 and arranged diametrically opposite are the recesses 16. This flange is also provided with the inclined portions 17 which slope gradually from the recesses 16 and their 100 lowest points meet as at 18.

From the foregoing it is obvious that upon swinging the door upon its pivoted connections the roller 15 will travel upon the upper edge of the flange 12. If the door 6 105 is swung to open position as shown in Fig. 2 the roller 15 will seat itself within one of the recesses 16 and thereby retain the door in this open position. In closing the door the same is moved until the roller 15 110 has been moved out of the recesses 16. The roller 15 will then travel down the incline

17 and finally seat itself at the point 18, wherein the door will be retained in closed position. It is also obvious that the door may be opened so as to permit a person to 5 pass through the doorway and the door will by its own weight return in closed position, but should the door be open to a full 45° it will be retained in open position. It is also apparent that the recesses 16 may be 10 eliminated in case it is not desired to retain the door in open position, or only one recess may be used when the door may be opened and retained open at either side of the doorway.

15 Having thus fully described my invention, what I claim as new and desire to secure by Letters Patent is:

The combination with a door casing and a swinging door arranged therein, of a plate 20 carried by the lower edge of said door, said plate having a lug projection formed with one end thereof and extending within said door, a depending pin having one end extending through the opposite end of said 25 plate and within said door, a pair of side

plates secured to the opposite faces of the door and having their edges resting upon the opposite sides of said plate, lugs depending from said plate, a roller journaled within said lugs and extending transversely of 30 said plate, a shoe secured within said door casing, a flange formed with said shoe, the upper edge of said flange having a pair of diametrically opposite recesses therein, said flange being cut away to form a pair of inclines having their highest points terminating adjacent said recesses and the lowest ends of said inclines terminating at a point upon said shoe at right angles to said recesses, said roller adapted to ride upon said 35 inclines and be seated within said recesses substantially as and for the purpose specified.

In witness whereof I have hereunto set my hand.

ALPHONSE ALARY.

Witnesses:
